UNITED STATES PATENT OFFICE.

FRANCIS W. CARPENTER, OF ST. PAUL, MINNESOTA, ASSIGNOR TO FOSSTON-CARPENTER COMPANY, OF ST. PAUL, MINNESOTA, A CORPORATION OF MINNESOTA.

DRIVING MECHANISM FOR WASHING MACHINES.

1,418,429.

Specification of Letters Patent. Patented June 6, 1922.

Application filed May 10, 1918. Serial No. 233,783.

To all whom it may concern:

Be it known that I, FRANCIS W. CARPENTER, a citizen of the United States, residing at St. Paul, in the county of Ramsey and State of Minnesota, have invented certain new and useful Improvements in Driving Mechanism for Washing Machines; and I do hereby declare the following to be a full, clear, and exact description of the invention, such as will enable others skilled in the art to which it appertains to make and use the same.

My invention relates to washing machines of the type wherein the clothes are contained within a rotary drum and the drum is rotated first in the one direction and then in the other, and is directed chiefly to the provision of improved driving mechanism and co-operating devices.

To the above ends, generally stated, the invention consists of the novel devices and combinations of devices hereinafter described and defined in the claims.

In the accompanying drawings which illustrate the commercial form of the machine, like characters indicate like parts throughout the several views.

Referring to the drawings:

Fig. 1 is a front elevation of the machine, some parts being broken away and some parts being sectioned;

Fig. 2 is a side elevation of the machine, some parts being broken away and some parts being in vertical section;

Fig. 3 is a detail view showing the motion reversing mechanism and co-operating clutch devices of the drive, some parts being sectioned, and some parts being separated on the line 3—3 of Fig. 2;

Fig. 4 is a section taken approximately on the line 4—4 of Fig. 3;

Fig. 5 is a section taken on the line 5—5 of Fig. 1;

Fig. 6 is a section taken on the line 6—6 of Fig. 1;

Fig. 7 is an enlarged section on the line 7—7 of Fig. 5.

The washing tank 12 herein employed is a square structure in horizontal cross section and has a semi-cylindrical bottom. The said tank may be constructed of any suitable material, but the rectangular portion thereof is preferably made of wood, while the semi-cylindrical bottom thereof is preferably made of sheet metal. This tank at

its four corners is supported by suitable legs 13, shown as angle irons. The legs at their lower ends are rigidly tied together by a cross-beam 14; and as this washing machine is preferably driven from a small electric motor 15, said motor is suitably mounted on the said cross-beam 14.

Working within the tank 12 is a cylindrical drum 16 preferably having a cylindrical shell made of perforated galvanized sheet metal. The cylindrical shell of this drum is provided with a door opening adapted to be closed by a suitable detachable door 17. (See Fig. 2.) This drum is directly driven by a short co-axial horizontal shaft 18 (see Figs. 2, 5, and 7,) that is journaled in and extends through a suitable bearing in one head of the gear housing 30 and also in other bearings hereinafter noted.

The opposite end of the drum 16 is provided with a simple truncheon 24 that is adapted to be dropped into the open seat of a bearing 25 suitably secured to the adjacent head of the tank 12. (See Fig. 2.)

The above described drum driving shaft 18 extends outward through and it is journaled in both walls of a two-part gear housing 30. (See Figs. 2, 3, and 5.) Rotatably mounted on the shaft 18 within the gear housing 30 is a pair of reversely facing laterally spaced beveled gears 31—31^a; and keyed to said shaft and working with limited sliding movement thereon between the said gears, there is a tubular ended clutch sleeve 32 which by a suitable half-clutch is adapted to be interlocked alternately with the said two gears. The clutch devices by which, as shown, this is accomplished, comprises clutch pins 33 on said gears and pin seats 34 in the opposite ends of said clutch sleeve. The said gears and clutch sleeves constitute part of the drum reversing mechanism, and which mechanism is further comprised as follows.

For directly shifting the reverse clutch sleeve 32 it is shown as intermediately connected to a yoke-like reversing lever 35 which at its upper end has trunnions 36 pivotally mounted in half-seats formed in part in each of the two sections of the housing 30. At its extreme lower end the lever 35 (see Figs. 3 and 5) is formed with a long vertical channel 37 in which works the crank end or pin 38^a of a crank shaft 38 which latter is journaled in suitable bearings, as

shown, formed in part in each of the two sections of the housing 30. The housing 30 at one side is formed with a flanged tubular extension 39 that connects it to another gear housing 40. Preferably the neck portion 39 and housing 40 are also two-part structures in which each half thereof is cast as an integral part of one of the halves of the housing 30, the two castings being flanged 10 at their abutting edges and rigidly, but detachably, connected by screws or bolts 41.

Journalized in the neck portion 39 is a horizontal countershaft 42 which at that end which projects into the housing 30 is provided with a beveled pinion 43 that is in constant mesh with both of the gears 31 and 31^a. At that end of the shaft 42 that projects into the housing 40 is secured a beveled gear 44 that is in constant mesh with a 20 beveled gear 45 which, in turn, is loose on a long upright driving shaft 46. Working within the housing 40 and keyed for rotation with the shaft 46, but arranged to slide vertically thereon, is a start and stop clutch 25 sleeve 47 that is adapted to be clutched, at will, to the loose beveled gear 45. The clutch device for this purpose, as shown, comprises clutch pins 48 on the gear 45 and co-operating pin seats 49 in the adjacent end 30 of the clutch sleeve 47. (See Figs. 3 and 6.) The clutch sleeve 47 has an annular channel that is engaged by the crank end of a short crank shaft 50 that extends through and is journaled in the outer wall of the 35 housing 40, and at its outer end is provided with a projecting lever 51 by means of which said shaft may, at will, be oscillated to thereby slide the clutch sleeve 47 into or out of interlocking engagement with the gear 45.

40 This lever 51 has connections which will be hereinafter described.

Directing attention again to Figs. 3 and 4, it will be noted that the hub of the gear 43 is in the form of an eccentric 52 and that 45 a driving dog 53 is mounted on the eccentric. This driving dog 53 is gravity held in engagement with the teeth of a ratchet wheel 54 that rotates with the crank shaft 38, but is preferably connected thereto by a yielding 50 device shown in Figs. 3 and 4 and comprising as follows: A semi-circular rod 55 at one end is secured to a lug 56 on the ratchet wheel 54, and at its other end works through a radially projecting lug 57 of the crank 55 shaft 38. A coiled spring 58 on the rod 55 is compressed between the lugs 56 and 57 and a nut 59 on the end of said rod limits the expansion of this spring. Said spring connection cushions the driving action of 60 the driving dog 53 and permits the driving force to be gradually absorbed and applied to rotate the crank shaft 38. This is important because under rotation of the crank shaft, the lever 35 will carry the clutch sleeve 65 32 alternately into engagement with the

clutch hubs of the two gears 31 and 31^a, and it will frequently happen that the particular stroke of the dog which should serve to accomplish the clutch engagement will take place when the clutch pins 33 are not aligned with the pin seats 34. When this happens, the spring 58 will yield and as soon as the pins and pin seats are properly aligned, the clutch engagement will follow without producing any undue strain or breakage of 75 parts.

To prevent over rotation of the crank shaft 38 under the action of the driving dog, I preferably apply a light friction device to the hub of the ratchet wheel 54. This friction device (see Fig. 3) is in the form of a spring-yoke 60 adapted to be adjusted by a screw 61 and having its projecting end anchored in a seat 62 of the housing 30. (See Fig. 3.)

It is, of course, obvious from the foregoing that when the shaft 42 is driven in a constant direction, the two gears 31 and 31^a will be driven in reverse directions and by the action of the crank shaft 38 and co-operating parts which effect the alternate interlocking engagement of the clutch sleeve 32 with the said gears, the drum will be given alternately several rotations in the one direction and then several rotations in the 95 opposite direction. The number of rotations the drum will be given in a constant direction without reversal will depend upon the number of teeth in the ratchet wheel or upon the length of stroke of the driving 100 dog.

Attention is here called to the peculiar form of the slot or channel 37 in the lever 35, (see Fig. 5) by reference to which it will be noted that the said slot at its upper and lower extremities is constructed to approximately fit the crank pin 38^a so that the movements of the crank pin in its upper and lower position will quite quickly accomplish that movement of the lever that is required 105 to shift the clutch sleeve 32 from interlocking engagement with the one gear into an interlocking engagement with the other gear, and the said crank pin when making its main movements from upper to lower, or 110 lower to upper positions, will clear, or at most but barely touch the reversely bulged sides of said slot 37 and during such time will leave the lever 35 nearly, or quite, stationary and locked.

The electric motor 15 may be arranged to drive the upright shaft 46 at a greatly reduced speed in various different ways, but preferably through a worm and gear. As shown, these connections are as follows: On 125 the lower end of said shaft 46 (see Fig. 1) is a worm gear 63. This worm gear works in a housing 64 that affords a bearing for the lower end of the shaft 46 and has a flanged base bolted to the cross beam 14.

- The upper shaft bearing of the housing 64 is connected to the lower portion of the gear housing 40 by a metal pipe or tube 65 that encloses the lower portion of said shaft 46.
- 5 The worm gear 63 is engaged by a worm 66 carried by a short shaft 67 to the projecting end of which a grooved pulley 68 is secured. A belt 69 runs over the pulley 68 and over a smaller grooved pulley 15^a secured to the 10 armature shaft 70 of the electric motor 15.
- It is highly desirable that when the machine is stopped for the purpose of placing clothes within the drum, or for removing clothes from the drum, that the drum be 15 brought to a stop position with the door opening on top. I provide a novel and efficient device for accomplishing this result, which device in its preferred form comprises as follows. (See Figs. 1, 5, and 7.)
- 20 The outer section of the housing 30 has a bearing hub 71, the outer surface of which is cylindrical except at the top where it is cut away at 71^a to reduce the projecting of the said hub from the axis of the shaft 18 (see particularly Fig. 7). Adjacent to the outer end of the hub 71 the shaft 18 is formed with a peripheral notch that affords a stop-shoulder or surface 72. Mounted to oscillate on the hub 71 and on a cap-screw 30 25 35 40 45 50 55 60 65 70 75 80 85 90 95 100 105 110 115 120 125 130 applied to the end of the shaft 18 is a crank arm 74 that is formed with the housing or hollow portion 74^a. The crank arm 74 is connected by a rod 75 to the intermediate portion of the clutch actuated lever 51 (see Fig. 1). Working within the housing 74^a and pivoted to a radially offset portion thereof is a stop dog 76 (again note Figs. 5 and 7). This dog 76 at its free end has a hooklike end or stop-shoulder that is adapted to engage the stop-shoulder 72 of the shaft 18 and, moreover, said dog at its free end has a laterally projecting cam pin 77 that rides upon the fixed hub 71. When the crank 74 is oscillated so as to carry the cam pin 77 onto the cylindrical portion of the hub 71, the stop dog 76 will be held in a position in which it will not engage the stop-shoulder 72 of the shaft 18, but when said crank is moved into the position shown in Fig. 7 so as to carry its pin 77 onto the flattened upper portion 71^a of said hub 71, the stop dog will then be permitted to engage said stop-shoulder 72, as shown in Fig. 7, and thereby stop the drum positively in a position in which its door opening will be on top or uppermost.
- When the clutch lever 51 is in the extreme position toward the left, in respect to Fig. 1, the clutch sleeve 47 will be interlocked to 60 the gear 45 and the drum driving mechanism will then be rendered operative to rotate the drum, assuming, of course, that the electric motor is in action; and at the same time, or by the same adjustment of said lever 51, the crank 74 will be moved into a position to carry the cam pin 77 of stop dog 76 onto the cylindrical portion of the cam actuated hub 71. Hence, under the above noted adjustment of the lever 51, the rotation of the drum will not in anywise be interferred with by the stop dog.
- In the preferred arrangement illustrated, the clutch lever 51 is arranged to be yieldingly set against accidental movements in any one of three positions, one extreme position of which has just above been described. This setting of the said lever may be, and preferably is, accomplished by providing the lever 51 with an ordinary yieldingly pressed pointed or rounded pin 78 of well-known construction which will engage any one of three circumferentially spaced depressions 79 formed in a segmental surface 79^a on the outer side of the gear casing 40 (see Fig. 1).
- If the clutch lever 51 be set in its intermediate position, the clutch sleeve 47 will be nearly but not quite moved out of interlocking engagement with the gear 45, and the crank 74 will then be set in such position that the cam pin 77 of stop dog 76 will then rest upon, or be immediately above the flattened or reduced surface 71^a of the fixed cam hub 71. Under these conditions, as soon as the notch in shaft 18 comes into registration with the nose of stop dog 76, the said nose will drop into engagement with stop shoulder 72 of said shaft (see Fig. 7) and thereby stop the drum with its door opening uppermost, since the slightly continued forward movement of the drum, acting on said dog and through the crank 74, rod 75, lever 51, and shaft 50, will be sufficient to complete the disengagement of the clutch sleeve 47 from the gear 45, and thereby disconnect the drum from the motor driven shaft 46.
- The drum, by the dog 76, will then be positively locked against forward movement in the direction of the movements of the hands of a clock, such directions being taken in respect to Figs. 1 and 7.
- The description above given assumes that the drum was running in the direction just stated during the time that the above operations took place. The automatic locking action described prevents starting of the machine while the person is taking clothes out of or putting clothes into the drum and is a very important feature. Before the drum can be again started, it must be rotated backward far enough to cause the hub 71 to raise the lock dog and release the crank 74 and lever 51 for movements toward the left; and then the said crank 74 and lever must be moved into extreme positions toward the left. This movement of the lever 51 to its extreme position at the left will carry the crank 74 of the dog 76 onto the cylindrical surface of the hub 71, and thereby set the dog out of position for action on the shoulder

72, and this will release the drum for continued forward movement in the direction stated. When the drum is filled with clothes it is a difficult operation to rotate the drum 5 backward from the position in Fig. 7, by movements of the lever toward the left, and moreover, even if this should be done, the lock dog would immediately lock the drum when it is again rotated by the driving mechanism, back to the position shown in Fig. 7. 10 If the lever 51 should be set in the position shown in Fig. 1 while the drum is being rotated in a reverse direction to that noted, or in an anti-clockwise direction, the automatic 15 locking of the drum will not take place until the drum is reversed and has been rotated in a clockwise direction far enough to form the engagement of shoulder 72 with the nose of the stop dog 76, but the locking of the drum 20 will take place at such time and the drum will be automatically stopped with its door open upward.

In the drawings, a reversible wringer of well known construction is indicated as an 25 entirety by the numeral 80; and for driving this wringer I provide the mechanism best shown in Figs. 1, and 3. To the upper end of the shaft 46 (see Fig. 3) is secured a clutch collar 81 that is mounted to directly 30 rotate in the upper portion of the housing 40. 46^a indicates a shaft that is axial with shaft 46, and in fact constitutes a detachable upper extension thereof. Rigidly secured to the lower end of shaft 46^a is a clutch collar 46^b. 35 This clutch collar 46^b and the clutch collar 81, on the end of shaft 46, have interlocking clutchlike engagement, so as to cause the two shafts 46 and 46^a to rotate together. Spaced from and surrounding the shaft 46^a is a tubular pipe or housing 82, the lower end of which 40 is mounted to oscillate in the upper portion of the housing 40, and the upper end of which is mounted to oscillate in a bearing bracket 83 secured to the upper portion of 45 one side of the tank and its supporting frame. The extreme upper end of this oscillatory housing 82 is extended into and secured to a two-part housing 84 to which latter the wringer 80 is rigidly secured by an offset bracket 85. (See Fig. 1.) 50

The housing 84 is preferably made in two parts centrally divided and rigidly secured together by bolts or screws. The housing 84 carries gearing driven by shaft 46^a and a 55 clutch is disposed in said housing adapted to be operated by a handle 91 carried on a shaft 90 to cause the gearing to drive the rolls of wringer 80 in either direction.

To hold the wringer in either of several 60 operative positions, the depending sleeve portion of the housing 84 is shown as provided with offset lugs in which is mounted a downwardly spring-pressed lock bolt 93 that is engageable with co-operating seats in the bearing bracket 83.

The wringer above described will be properly driven in any one of its several different positions, but this, of course, is a feature which is not broadly new with my invention. With the described construction, however, 70 the wringer with the gear casing 84, tube 82, and shaft 46^a, may, at will, be lifted from working position and removed from the machine and, of course, it may be also easily replaced. 75

What I claim is:

1. The combination with a rotary member adapted to be reversely driven, of a pair of reversely driven gears, a clutch member connected to rotate said rotary member and arranged for driving connection alternately with said two reversely driven gears, and means for alternately moving said clutch member into interlocking engagement with the said two gears, said means comprising a pawl and ratchet device driven with a timed action in respect to said reversely driven gears, said means further comprising a spring connection for cushioning the driving action of said pawl and ratchet device. 80

2. The combination with a rotary member adapted to be reversely driven, of a power driven shaft, a second shaft, co-operating gears, and a start and stop clutch for connecting said two shafts a third shaft connected to said rotary member, a reversible drive for connecting said second shaft to said third shaft, said reversible drive including a reversing clutch, a reverse lever for operating said reversing clutch, a crank for oscillating said reversing lever, a ratchet wheel connected to said crank, and a pawl driven by said second shaft and operating on said ratchet wheel, and a spring carried by said ratchet wheel through which the crank 100 is actuated. 95

3. The combination with a rotary member adapted to be reversely driven, of a power driven shaft, a second shaft, co-operating gears and a start and stop clutch for connecting said two shafts, a third shaft connected to said rotary member, a reversible drive for connecting said second shaft to said third shaft, said reversible drive including a reversing clutch, a reverse lever 115 for operating said reversing clutch, a crank for oscillating said reversing lever, a ratchet wheel connected to said crank, a pawl driven by said second shaft and operating on said ratchet wheel, and a cushioning spring in 120 the connection between said crank and ratchet wheel.

4. The combination with a rotary member adapted to be reversely driven, of a power driven shaft, a second shaft, co-operating 125 gears and a start and stop clutch for connecting said two shafts, a third shaft connected to said rotary member, a reversible drive for connecting said second shaft to said third shaft, said reversible drive includ- 130

ing a reversing clutch, a reverse lever for operating said reversing clutch, a crank for oscillating said reversing lever, a ratchet wheel connected to said crank, a pawl driven by 5 said second shaft and operating on said ratchet wheel, and a stop device adapted to be set to stop the said third shaft in a predetermined position.

5 machine having in combination a rotary member, means for rotating the same, comprising a clutch element, a co-operating clutch member for driving said element, a normally inactive stop device for stopping 70 said rotary member in a predetermined position, and a connection between said stop device and said clutch mechanism for moving

5. The combination with a rotary member
10 adapted to be reversely driven, of a power
driven shaft, a second shaft, co-operating
gears and a start and stop clutch for connect-
ing said two shafts, a third shaft connected
15 to said rotary member, a reversible drive
for connecting said second shaft to said third
shaft, said reversible drive including a re-
versing clutch, a reverse lever for operating
said reversing clutch, a crank for oscillating
20 said reversing lever, a ratchet wheel con-
nected to said crank, a pawl driven by said
second shaft and operating on said ratchet
wheel, a stop device adapted to be set to stop
the said third shaft in a predetermined posi-
25 tion, and a connection between said stop de-
vice and said start and stop clutch, whereby
further forward rotation of said rotary
member acting through said stop device will
throw said start and stop clutch out of
30 action.

6. The combination with a rotary member
adapted to be reversely driven, of a power-
driven shaft, a second shaft, co-operating
gears, and a start and stop clutch for con-
necting said two shafts, a third shaft con-
35 nected to said rotary member, a reversible
drive for connecting said second shaft to
said third shaft, said reversible drive in-
cluding a reversible clutch, a reverse lever
for operating said reversing clutch, a crank
40 for oscillating said reversing lever, a ratchet
wheel connected to said crank, a pawl driven
by said second shaft and operating on said
ratchet wheel, a stop device adapted to be
set to stop the said third shaft in a predeter-
45 mined position, and a connection between
said stop device and said start and stop
clutch, whereby the further rotation of said
rotary member, acting through said stop de-
vice, will throw said start and stop clutch
50 out of action, the connection between said
stop device and said start and stop clutch
serving also to set said stop device in a posi-
tion for action.

7. A device of the class described having
55 in combination a rotary member, means for
rotating the same including a clutch ele-
ment, a clutch element for driving said ele-
ment, a stop device normally in inoperative
position adapted to engage and stop said ro-
60 tary member and react to cause the first
mentioned clutch element to stop and be
moved out of engagement with the second
mentioned clutch element by the continued
movement of the latter.

8. A driving mechanism for a washing
65

said clutch means to partly released posi-
tion and moving said stop device to opera-
tive position to engage and stop said rotary
member, said stop device reacting to stop
said clutch element whereby the same will
be completely thrown out of engagement
70 with said clutch member by continued move-
ment of the latter.

9. The combination with a member adapt-
ed to be rotated and a shaft carrying said
member, of a normally inactive stop device
to engage said shaft for determining the po-
sition in which said rotary member will be
80 stopped, and means for rotating said mem-
ber including a clutch, and a connection
whereby a partial release of said clutch will
throw said stop device into operative posi-
85 tion to engage and stop said shaft.

10. In a washing machine, the combina-
tion with a rotary drum having a door in
the shell thereof and a shaft carrying the
drum having a notch in one end, of means
90 for rotating the same, and a stop device in-
cluding a pawl adapted to engage said notch
which, when rendered active, serves to stop
said drum with its door uppermost.

11. In a washing machine, the combina-
tion with a tank, of a rotary drum working
in said tank and having a door in its shell,
means for rotating said drum including a
start and stop clutch, and a normally in-
95 active stop arranged to be placed in opera-
tive position by partial disengagement of
said clutch which, when placed in operative
position, serves subsequently to stop the
drum with its door uppermost.

12. In a washing machine, the combina-
tion with a tank, of a rotary drum working
in said tank and having a door in its shell,
means for rotating said drum including a
start and stop clutch, a normally inactive
105 stop which, when rendered active, serves to
stop the drum with its door uppermost, and
a connection between said stop device and
clutch whereby the further rotation of the
drum, acting through said stop device, will
110 automatically throw said clutch out of ac-
tion.

13. In a washing machine, the combina-
tion with a tank, of a rotary drum working
in said tank and having a door in its shell,
means for rotating said drum including a
115 start and stop clutch, a normally inactive
stop which, when rendered active, serves to
stop the drum with its door uppermost,
and a connection between said stop device
and clutch whereby the further rotation of
120

14. In a washing machine, the combina-
tion with a tank, of a rotary drum working
in said tank and having a door in its shell,
means for rotating said drum including a
125 start and stop clutch, a normally inactive
stop which, when rendered active, serves to
stop the drum with its door uppermost,
and a connection between said stop device
and clutch whereby the further rotation of
130

- the drum, acting through said stop device, will automatically throw said clutch out of action, a partial releasing movement of said clutch serving to render said stop device 5 active.
14. The combination with a rotary member and means for rotating the same including a clutch, said rotary member having a shaft and said shaft having a stop shoulder, 10 of a crank element mounted to oscillate on said shaft, a stop dog carried by said crank element and operative on the stop shoulder of said shaft to stop said rotary member in a predetermined position, and a cam surface 15 operative on said dog to hold the same inoperative in one position and operative in another position of said crank element.
15. The combination with a rotary member and means for rotating the same including a clutch, said rotary member having a shaft and said shaft having a stop shoulder of a crank element mounted to oscillate on said shaft, a stop dog carried by said crank element and operative on the stop shoulder 20 of said shaft to stop said rotary member in a predetermined position, a cam surface operative on said dog to hold the same inoperative in one position and operative in another position of said crank element, and a connection 25 between said clutch and crank element whereby a partial releasing movement of said clutch will set said crank element in a position to release its stop dog for automatic action.
16. The combination with a rotary member and means for rotating the same including a clutch, said rotary member having a shaft and said shaft having a stop shoulder, of a crank element mounted to oscillate 30 on said shaft, a stop dog carried by said crank element and operative on the stop shoulder of said shaft to stop said rotary member in a predetermined position, a cam surface operative on said dog to hold the same inoperative in one position and operative in another position of said crank element, and a connection 35 between said clutch and crank element whereby the further rotation of said rotary member, acting through said stop dog and crank element, will automatically throw said clutch out of action.
17. The combination with a rotary member and means for rotating the same including a clutch, said rotary member having a shaft and said shaft having a stop shoulder, of a crank element mounted to oscillate on said shaft, a stop dog carried by said crank 40 element and operative on the stop shoulder of said shaft to stop said rotary member in a predetermined position, a cam surface operative on said dog to hold the same inoperative in one position and operative in another position of said crank element, and a connection 45 between said clutch and crank element whereby the further rotation of said rotary member, acting through said stop dog and crank element, will automatically throw said clutch out of action.
18. In a washing machine, the combination with a rotary drum and a motor, of means for reversely rotating said drum from 50 said motor comprising three shafts, the first of which is constantly driven from said motor and the third of which rotates with said drum, gears and a co-operating start and stop clutch for connecting said first 55 and second shafts, a pair of reversely facing beveled gears loose on said third shaft, a beveled pinion on said second shaft meshing with said reversely facing gears and reversely driving the same, a reversing clutch 60 sleeve slidably connected with said third shaft and having alternate clutch engagement with said reversely facing gears, a reversing lever operative on said reversing clutch, a crank operative on said reversing 65 lever, and a pawl and ratchet device operating yieldingly said crank from said second shaft.
19. A device of the class described having in combination a rotary member, means 70 for rotating said member including a clutch element, a co-operating clutch member for driving said element, a stop normally in inoperative position adapted to be moved to engage said rotary element, means for partially disengaging said clutch element from said clutch member and moving said stop device to engage said rotary member and stop the same, said stop device re-acting through said rotary member to stop said 75 clutch element whereby the same will be completely disengaged from said clutch member by the continued movement of the latter.
- In testimony whereof I affix my signature 80 in presence of two witnesses.
- FRANCIS W. CARPENTER.
- Witnesses:
- HARRY D. KILGORE,
F. D. MERCHANT.
